US0D1067468S

(12) **United States Design Patent** (10) **Patent No.:** **US D1,067,468 S**
(45) **Date of Patent:** **** Mar. 18, 2025**

(54) **TRIANGULAR MODULAR FLORAL ARCH**

(71) Applicant: **Syndicate Sales, Inc.**, Kokomo, IN (US)

(72) Inventor: **Trent A. Harshman**, Galveston, IN (US)

(73) Assignee: **Syndicate Sales, Inc.**, Kokomo, IN (US)

(**) Term: **15 Years**

(21) Appl. No.: **29/870,876**

(22) Filed: **Feb. 7, 2023**

(51) **LOC (15) Cl.** **08-99**

(52) **U.S. Cl.**

USPC **D25/100**

(58) **Field of Classification Search**

CLAIM

The ornamental design for a triangular modular floral arch, as shown and described.

DESCRIPTION

FIG. 1 is a front left perspective view of the triangular modular floral arch incorporating our new design;

FIG. 2 is a front right perspective thereof;

FIG. 3 is a rear view thereof;

FIG. 4 is a front view thereof;

FIG. 5 is a bottom view thereof;

FIG. 6 is a top view thereof;

FIG. 7 is a left view thereof; and,

FIG. 8 is a right view thereof.
